AUXILIARY CALKING FLANGE FOR TUNNEL LINING JOINTS

John Marshall Ribble, Petersburg, Va.

Application August 15, 1938; Serial No. 225,041

6 Claims. (Cl. 61—45)

This invention relates to adjunctive calking flanges adapted to be employed in connection with light gauge plate tunnel lining.

The general practice in building a tunnel is to line the hole progressively as the excavation proceeds, quite up to the heading or end of the excavation, with a line of light steel rectangular plates flanged inwardly on all four sides, said plates having the curvature of the circumference of the tunnel, being placed in position as the excavation proceeds with their flanges in abutment, and being bolted together through the flanges.

The concrete lining which supplements the steel plate lining is usually kept at some distance back of the heading so that the workmen and apparatus associated with the pouring of the concrete will not be in the way of the men and apparatus employed in the excavation at the heading. Thus between the heading and the concrete, there will be found a length of from 100 to 300 feet, for example, of exposed steel lining with the bolted together flanged joints.

It is generally necessary to maintain the air in the tunnel while under construction, at a pressure sufficiently above atmosphere to keep ground water out of the tunnel. The joints between the steel lining plates provide a fruitful avenue for the escape of the compressed air from the tunnel so that an extravagant amount of power may be required to maintain the necessary air pressure.

The present invention has for its object the provision of auxiliary thin flanges adapted to be applied to the opposite sides of the flanged joints of the steel lining plates after the latter have been bolted in place, and extending beyond the edges of said flanged joints forming a channel in which calking compound may be inserted for sealing the joints against air leakage.

Inasmuch as the curvature of the plates lining the tunnel is frequently distorted by the outside load which they support, it is therefore an object of the invention to make the auxiliary calking flanges of such thinness or quality of material that they can be bent or sprung somewhat from their normal shape to conform to the curvature of the plates to which they are attached.

Still another object of the invention is to provide an auxiliary calking flange so constructed that it may be quickly attached merely by loosening the bolts which secure the plates, but without removing said bolts.

Other objects of the invention will appear as the following description of a preferred and practical embodiment thereof proceeds.

In the drawings which accompany and form a

part of the following specification and throughout the several figures of which the same characters of reference have been employed to designate identical parts:

Figure 1 is a vertical section through a tunnel illustrating the employment of the auxiliary calking flanges of the present invention;

Figure 2 is a cross section through the joint between two lining plates and the auxiliary calking flanges;

Figure 3 is a fragmentary view in elevation illustrating the construction of one of the auxiliary calking flanges;

Figure 4 is a cross section through a joint showing a modified form of the invention;

Figure 5 is a perspective view of one of the steel lining plates;

Figure 6 is a view similar to Figure 2 and shows a modified form of calking flange;

Figure 7 is a perspective view of the calking flange illustrated in Figure 6;

Figure 8 is a cross section through a joint between two lining plates showing a further modified form of auxiliary calking flange; and

Figure 9 is a perspective view of the calking flange shown in Figure 8.

Referring now in detail to the several figures, the numeral 1 represents a tunnel excavated up to the heading 2 which is of earth or rock, the tunnel being lined as far as the heading with a lining of light gauge plates 3. In the posterior portion of the tunnel the plates forming the steel lining are embedded in a concrete lining 4. It will be noted that the steel lining is exposed for quite a distance from the heading to the concrete lined portion of the tunnel, this being for a reason that has been explained in the prefatory paragraphs of the specification.

The steel plates 3 are each arcuate in the circumferential direction of the tunnel and rectilinear in the longitudinal direction, each being formed with inwardly extending flanges 5 along their four sides, the corners of the flanges being preferably welded together as indicated at 6 in Figure 5, in the interest of rigidity. The plates are preferably arranged in staggered relation and secured together both along their arcuate and straight sides by means of bolts 7 passing through apertures 8 in said flanges and nuts 9 which are tightened against the flanges.

As has been stated in the early portion of the specification, there may be a length of from 100 to 300 feet of exposed steel lining representing many hundred feet of juncture between the flanges which forms a major source for leakage of

the compressed air with which the tunnel is charged for the purpose of keeping ground water out of the tunnel. The additional power required to produce air pressure to off-set this leakage is great so that in the interest of economy it would be highly desirable to calk the joints between the flanges to prevent this air leakage. However, due to the thinness of gauge of the plates which is as a rule only $\frac{1}{16}$ or a quarter inch, the adjacent ends 10 and 11 of abutting flanges do not afford large enough area for the lodgment of enough calking compound to be effective. Consequently, as a rule, the joints are left uncalked.

15 The adjunctive calking flange forming the subject of the present invention consists, in that embodiment illustrated in Figures 1 to 3, inclusive, of a strip 12 of thin material preferably having one longitudinal edge crimped to form a channel 13. The opposite longitudinal edge of the strip 12 is preferably formed at proper intervals with recesses 14 adapted to straddle the bolt shanks when the nuts 9 are backed off sufficiently to permit the insertion of the adjunctive calking flange between said nuts and the adjacent face of the flange 5. The width of the recesses 14 is preferably just sufficient to permit the bolt shanks to freely enter, so that when the nuts are screwed down again, they will clamp the auxiliary calking flanges in place. There is preferably enough tolerance between the edges of the recesses 14 and the bolts to permit the auxiliary calking flanges to be shifted laterally of said recesses as well as in the depthwise direction with respect to the flanges 5, and the material of which the strip 12 is made should be capable of bending or springing so that it may be accommodated in shape to any deformation which may take place in the curvature of the plates 3. Figure 2 shows that when two of the auxiliary calking flanges are in place on opposite sides of two abutting flanges, the re-entrant sides of the channels 13 confront one another forming a trough to receive the calking compound. Preferably, the auxiliary calking flanges extend a slight distance below the ends 10 and 11 of the flanges 5 as is indicated at 15 in Figure 2 to increase the depth of the calking trough 16 and increase the length of the leakage path between the calking plastic and the joint. It is of course not essential that the extra depth should be thus provided. The calking compound which customarily is of a tarry or bituminous nature is applied by means of a trowel or other suitable tool, the calking trough being preferably filled.

60 The auxiliary calking flanges are easily installed, it being unnecessary to remove any of the bolts and they may be left in place to be embedded in the concrete lining. On account of their light and flexible nature, they are economical, as regards cost to manufacture, and adaptable to any curvature. As a rule however, they come in two shapes, some rectilinear and some having the same curvature as the original curvature of the plates with which they are to be used.

65 The shape of the channels 13 is quite immaterial, in fact, it is sometimes desirable and sufficient to dispense with the channels 13, and by installing the auxiliary calking flanges in projecting relation as regards the ends 10 and 11 of the flanges 5, as shown in Figure 2 to form a channel bounded laterally by the projecting edges of said auxiliary calking flanges.

70 The auxiliary calking flanges are not designed 75 to add any structural stability to the lining plates

or their flanges, but are provided for the sole purpose of forming a calking channel over the joint between abutting plates.

Figure 4 shows a slightly modified form of the invention in which the plates 17 are themselves 5 integrally formed with the calking channels 13.

In that form of the invention illustrated in Figures 6 and 7, the auxiliary calking flanges take the form of a unit 17 of general U-shaped cross section having the side flanges 18 and 19, 10 spaced apart in substantially parallel relation and at such distance as to snugly embrace the abutting flanges 10 and 11 of adjacent plates 3. The bight or bend 20 of the unit preferably has a diameter greater than the distance apart of 15 the side flanges 18 and 19 so as to afford a calking trough or channel of adequate size to embed the ends of the abutting flanges and to seal the joint. Figure 6 shows that the bight or bend 20 is adapted to be filled with the calking compound, represented by the reference character 21. The unit is then pushed over the abutting flanges with the indentations 14 straddling the shank of the bolt 8, it being assumed that the nut has been backed off sufficiently to permit the side flanges to slide 25 between the bolt head and the nut and the intervening flanges. The auxiliary calking flange unit is preferably pressed upward until the ends of the abutting flanges are buried to some distance in the calking compound so as to increase the 30 leakage path between the calking compound and the joint. By tightening the nut 9, the calking flange unit may be secured in place.

35 Figures 8 and 9 show a further modified form of the invention in which the bolts which secure 35 the adjacent plate flanges together are not relied upon to hold the auxiliary calking flange unit in place. In this form of the invention, the auxiliary calking flange unit comprises a resilient sheet metal member having the side flanges 22 40 and 23 connected by the bight portion 24 of the unit. The resiliency may reside either in the side flanges or solely in the bight portion. In any event, the normal relation of the side flanges is slightly convergent as shown in Figure 9. To 45 install this auxiliary calking flange unit the side flanges are spread by the insertion of a suitable tool into a relation of substantially parallelism, or sufficiently to enable them to be slipped upon a pair of abutting plate flanges. The spreading 50 tool may be removed whereupon the native resiliency of the unit will cause the side flanges 22 and 23 to grip the plate flanges, holding the auxiliary calking flange unit in place.

55 While I have in the above description disclosed what I believe to be a preferred and practical embodiment of the invention, it will be understood to those skilled in the art that the details of construction and the shape of the auxiliary flanges may be varied to suit the exigencies 60 of the particular use to which they may be applied.

What I claim is:

1. In combination with a tunnel lining consisting of a plurality of flanged plates with the 65 flanges of adjacent plates abutting forming a linear joint, auxiliary calking means adapted to be clamped along the opposite sides of said abutting flanges and extending beyond the tops of 70 said flanges, the extending part of said means being shaped to define a calking-receiving channel.

2. In combination with a tunnel lining consisting of a plurality of flanged plates with the flanges of said plates abutting forming a linear 75

joint, an auxiliary calking flange unit comprising a doubled strip of sheet material of deep U-shaped cross section having its opposite sides embracing abutting plate flanges, and having its bight forming a calking compound-receiving trough into which the ends of the abutting plate flanges enter when the calking flange unit is in place.

3. In combination with a tunnel lining consisting of a plurality of flanged plates with the flanges of said plates abutting forming a linear joint, an auxiliary calking flange unit comprising a doubled strip of sheet material of deep U-shaped cross section having its opposite sides embracing abutting plate flanges and having its bight forming a calking compound-receiving trough into which the ends of the abutting plate flanges enter when the calking flange unit is in place, the sides of said unit having notches indented from the free edges of said sides adapted to straddle the bolts which secure the plate flanges together, whereby said auxiliary calking flanges may be secured between the heads and nuts of said bolts.

25 4. In combination with a tunnel lining consisting of a plurality of flanged plates with the flanges of said plates abutting forming a linear joint, an auxiliary calking flange unit comprising a doubled strip of resilient sheet material of deep U-shaped cross section having its opposite sides resiliently embracing said abutting plate flanges for holding said auxiliary calking flange unit in place, said unit having its bight forming a calking compound-receiving trough into which the

ends of the abutting plate flanges extend when said calking flange unit is in position.

5. Auxiliary calking flange comprising a deformable sheet metal strip adapted to be placed in duplicate along opposite sides of the abutting flanges of tunnel lining plates, said strip having an opening adapted to be aligned with a bolt which passes through the abutting flanges of said lining plates whereby said strip may be secured to said abutting flanges, the outer margin of said strip being formed with a channel adapted to extend beyond the tops of said abutting flanges, and the margins of the strips when they are arranged in duplicate on opposite sides of said abutting flanges cooperating to define a calking trough over the linear joint between said abutting flanges.

6. Auxiliary calking flange comprising a deformable strip of sheet metal having an indentation in one longitudinal edge adapted to be aligned with and receive a bolt which secures in abutting relation the adjacent flanges of adjacently placed tunnel lining plates, the auxiliary calking flange being adapted to be clamped in duplicate to the opposite sides of said abutting plate flanges by a bolt and nut which holds said plate flanges together, the outer margin of said strip being formed with a channel adapted to match with the corresponding channel of the oppositely disposed auxiliary calking flange when they are arranged in duplicate on opposite sides of said abutting flanges to form a calking trough over the linear joint between said abutting flanges.
